UNITED STATES PATENT OFFICE.

GEORGE W. MASON, OF SHARON, PENNSYLVANIA.

WRENCH.

No. 884,748.

Specification of Letters Patent.

Patented April 14, 1908.

Application filed December 27, 1906. Serial No. 349,741.

To all whom it may concern:

Be it known that I, GEORGE W. MASON, a citizen of the United States, residing at Sharon, in the county of Mercer and State of Pennsylvania, have invented certain new and useful Improvements in Wrenches; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to an improved quick-acting wrench and it comprises a bar fitted with a stationary head, a rack formed along a portion of the length of said bar, a moving head carrying means for locking the same rigid with said bar, said head being formed in two parts with intermediate adjusting device, and the invention further consists in the certain details of construction and combination of parts, as will be fully described hereinafter.

In the accompanying drawings;—Figure 1 is a side elevation of my improved wrench, the same being constructed and arranged in accordance with my invention. Fig. 2 is an inverted plan view of the same, a part of which is shown in section, said section being taken on the line z, z of Fig. 1. Fig. 3 is an end sectional elevation on the line X, X of Fig. 1. Fig. 4 is a similar view on the line y, y of the same figure. Fig. 5 is a detailed view of the right and left hand adjusting screws, showing the manner in which they are coupled together. Fig. 6 is an end elevation of the forward jaw of the moving head, showing the form of the opening therethrough.

To put my invention into practice and thereby provide a quick-acting wrench, I provide a bar 1, of suitable length and material, and at one end thereof, form a head or jaw 2, the same being fixed and at right-angles to the bar 1. This bar is provided along a portion of its length with a ratchet of integral projecting parts 3, and a portion of the end opposite to the head 2, formed into a handle. Operating along the length of the bar 1, is a moving head 5, comprising a solid piece of metal, with an opening 20 to fit neatly about the bar 1, and with a downward extension to form the other jaw of the wrench. This moving head is formed with

an integral rearwardly-extending piece 7, adapted to operate between one edge of the bar 1 and a supplemental moving part 8, at the rear of the head 5, the two being adjustably joined together by right and left-hand threaded bolts, in such manner that the two may be moved toward and away from each other. This connection of the right (10) and left (12) screws is formed by providing the one part with an enlarged annular boss 11, which when milled on the periphery answers the purpose of a thumb-nut, the said enlargement being formed with a socket for the reception of a tapering integral part of the other threaded bolt 12, the latter bolt being provided with a collar 13. These two parts, last described, are loosely connected the one with the other by a pin 15, passing through an opening 14 of larger diameter, which opening is formed through the tapering part above mentioned. By this construction of the connection between the right and left-hand screws, the one will operate with the other without binding when the two are not in direct line. This right and left connection joins the moving head 5 with the supplemental head 8, by entering threaded sockets 6 and 9, formed respectively in said heads, thereby providing a quick-acting adjustment to move the head 5, toward or away from the stationary jaw 2. To hold these moving heads 5, 8, stationary or fixed to the bar 1, a transverse slot 15 is formed through the supplemental head 8, the said slot being located immediately beneath the bar 1, and is adapted to receive a lock bar 14 which enters between the teeth 3 of the rack. This lock bar 14 is formed at one end with a "T" head and is fitted with a large headed screw 16 at the other, which arrangement will prevent end movement of the same. Arranged beneath this lock bar 14, is a spiral spring 18, which tends to keep said lock bar engaged with the ratchet 3, the said spring being arranged in a recess and confined therein by a pin 18' and short screw 17, as will be best seen by reference to Fig. 4 of the drawings.

The operation of the above-described wrench is as follows. The projecting "T" head and the screw head 16, is taken between the thumb and forefinger and pressed downward to free the lock bar 14 from the ratchet 3, and when in this position the moving heads 5 and 8, may be free to move along the length of the bar 1 in either direction, and

when the two jaws of the wrench are approximately sized to correspond with the nut operated upon, the lock bar is released to enter the adjacent space of said ratchet.

5 The thumb nut 11 is now operated to move the jaw 5 in close relation with the nut operated upon.

It will be noticed that, by forming the teeth of the rack 3, in such manner as to 10 leave a space 21 between the edge of the bar and the ends of the teeth, a shoulder will be formed on either side, which will engage with corresponding shoulders 20, formed in the sliding heads, (see Fig. 6,) thereby removing 15 a greater part of the strain from the teeth 3. This construction of shoulders will permit the sliding heads to move freely along the length of the bar 1 without interfering or binding on the teeth, the said heads having a 20 clearance over the top and sides.

Another means of relieving the strain between the two moving heads and from the teeth of the rack is the rearwardly-extending portion 7, which transfers said strain from 25 the jaw to the top of the supplemental head 8.

Slight modifications and changes may be made in the details of construction, without departing from the spirit of the invention.

Having thus described my invention, 30 what I claim, and desire to secure by Letters Patent, is:—

1. In combination, a bar provided with a fixed jaw, a head movable on the jaw, a supplemental head movable on the jaw, said

first named head having an extension formed 35 therewith passing between one side of the bar and the inner wall of the supplemental head, means for moving said heads toward or away from each other, and means carried by the supplemental head engaging the bar 40 to hold the supplemental head against movement on the bar.

2. In combination, a bar provided with a fixed jaw, a head movable on the jaw, a supplemental head movable on the jaw, said 45 first named head having an extension formed therewith passing between one side of the bar and the inner wall of the supplemental head, means for moving said heads toward or away from each other, and means 50 for holding the supplemental head against movement on the bar.

3. In combination a bar provided with a fixed jaw, a head movable on the jaw, a supplemental head movable on the jaw, said 55 first named head having an extension formed therewith passing between one side of the bar and the inner wall of the supplemental head, screw means for moving said heads toward or away from each other, and means for holding the supplemental head against 60 movement on the bar.

In testimony whereof, I affix my signature, in presence of two witnesses.

GEORGE W. MASON.
